UNITED STATES PATENT OFFICE.

ARTHUR R. ADAMSON, OF LOS ANGELES, CALIFORNIA.

SHREDDING MACHINE.

Application filed March 12, 1925. Serial No. 15,079.

This invention relates to a machine, the function of which is to shred material of any kind. The general object of the invention is to produce a machine of simple construction which will have a relatively large capacity and in which the degree of fineness of the shredding can be regulated as desired; also to provide a machine of this type in which the speed and force with which the material is fed to the shredding devices can be regulated, and to provide automatic means for arresting the feeding operation at a predetermined point. One of the objects of the invention is to provide a machine of this kind with a shredder or shredder drum having features of construction which facilitate the replacement and adjustment of the shredding devices; and to provide special means for preventing injury to the shredding devices in case a foreign substance should be accidentally fed to the shredding devices with the material to be shredded.

Further objects of the invention will appear hereinafter.

The invention consists in the novel parts and combination of parts to be described hereinafter, all of which contribute to produce an efficient shredding machine.

A preferred embodiment of the invention is described in the following specification, while the broad scope of the invention is pointed out in the appended claims.

In the drawings:

Fig. 1 is a vertical section through a portion of the machine embodying my invention, certain parts being broken away.

Fig. 2 is a plan of the machine shown in Fig. 1, certain parts being broken away and shown in cross section.

Fig. 3 is a side elevation particularly illustrating details of the guideways for feeding a material to the shredding devices, and also illustrating the automatic means for arresting the operation of the feeding mechanism.

Fig. 4 is a vertical cross section through one of the feed carriages, certain parts being shown in elevation. This view particularly illustrates the means for releasing the carriage to permit it to be moved back or forth along the feed screw, and also illustrates details of the means for holding the follower in its operative or inoperative position.

Fig. 5 is a horizontal cross section taken through two adjacent shredding devices and showing a short portion of the body of the drum.

Fig. 6 is a horizontal section taken about on the line 6—6 of Fig. 1, and particularly illustrating details of the means for adjusting the angle of the shredding devices. 60

In practicing the invention, I provide a frame 1 of any suitable construction, the body of which may be mounted upon short columns standing on the floor. In this frame I provide a rotary member 3 having a plurality of shredding devices mounted thereupon, and I provide means for driving the rotary member and for feeding the material to be shredded to the shredding devices. The rotary member 3 is preferably in the form 70 of a drum carrying a plurality of shredding devices 4 disposed circumferentially around the vertical axis of rotation of the drum. The drum is preferably carried on a substantially vertical shaft 5, and each shredding 75 device 4 is preferably in the form of an elongated bar 6 (see Fig. 5). The adjacent shredding devices are disposed slightly apart so as to form a gap 7 between them, at which point the shredding operation takes place. 80 This gap permits the material as it is shredded to pass through the wall of the drum.

In the present instance I feed the material to be shredded to the drum from the outer 85 side, and for this purpose I provide a plurality of guideways 8 which are disposed substantially radially from the axis of the drum, each guideway being provided with feeding mechanism 9 for feeding forward 90 the material in the guideway. The feeding mechanism 9 may be of any suitable construction, but in any case it is provided with automatic means for arresting the feeding movement at a predetermined point; this is 95 to prevent any possible injury to the mechanism through carrying the feeding movement too far.

In the present instance each feeding mechanism includes a feed screw 10 which extends 100 longitudinally with the guideway 8 (see Fig. 3). Each feed screw is driven through its own individual clutch 11 which is preferably a friction clutch. The feeding mechanism also includes a carriage 12 having a split nut 13 for engaging the feed screw so that in the operation of the machine the carriage 12 will move inwardly toward the drum. The carriage carries a follower 14 which is in the form of a plate which may project across 110 the guideway (see Fig. 2). This plate is preferably mounted to swing on a pivot or

pin 15, and suitable means is provided to enable it to swing back against the inner face of the carriage to enable the follower to pass material piled in the guideway when moving the carriage out toward its end. For this purpose, the follower may be provided with a short arm 16 having an opening to receive a removable pin 17 (see Fig. 4). When the pin 17 is removed, the follower 10 may be swung back against the face of the carriage.

In order to enable the split nut 13 to be opened up to disengage the threads of the feed screw 10, I provide a cam lever 18 which has a cam arm 19 which fits in between two inclined jaws 20 pivoted at 21 and pressed together by a spring 22 received on a bolt 23. The spring 22 holds the jaws 20 yieldingly in position, so that their interrupted threads 24 on their inner sides engage the thread of the screw. By moving the lever 18 in a direction to move the cam 19 outwardly or toward the right, as viewed in Fig. 4, these jaws will be spread apart to 25 disengage the split nut from the feed screw. When in this position evidently the carriage can be moved freely back or forth on the guideway.

Corresponding to each feed screw 10 I 30 provide a substantially vertical feed shaft 25 (see Fig. 3) and the lower end of this shaft is provided with a friction clutch 11 already referred to. The friction clutch 11 includes a sliding collar 26 which is normally 35 pressed down on the driven collar 27 by means of a weighted lever 28, said lever having two toes 29 (see Fig. 3), the lower one of which engages the outer end of a clutch lever 30 pivoted at 31 and having a short 40 arm 32 with pins 33 attached to a slip collar 34 on the sliding collar 26.

When the carriage 12 has completed its travel, a pin or abutment 35 upon it engages a pin 36 which projects down from the clutch 45 lever 30 and this swings the lever 30 downwardly. This movement swings the weight 37 on the lever 28 vertically over the pivot 38 of the yoke having the toes 29 and the weight descends on the right so that the uppermost toe would engage the end of the lever 30 and hold this lever depressed, thereby holding the clutch open. The feed screw 10 is driven through spiral gears 39 and 40 (see Fig. 2).

Referring again to the shredding devices 5, special attention is called to the bars 6; these shredder bars are preferably of substantially triangular cross section with the long sides of the triangles disposed outwardly and with vertices of the triangles disposed inwardly. In this way each bar presents an inclined face 41 which is inclined at an angle of about 45 degrees (see Fig. 5) to the circumferential line passing 60 through the axes of the bars. Each face 41

is provided with a shredding blade 42 which may be countersunk into the face and secured by suitable countersunk screws 43. Each bar may be adjusted on its vertical axis, which axis lies substantially in the 70 plane of the long side of the triangle so that the shredding edge 44 of each blade projects slightly beyond the outer face 45 of the bar which is next in advance with respect to the direction of rotation indicated by the arrow 75 in Fig. 5. Hence it will be seen that as the material being shredded is pressed against the outer face of the drum, the shredding edges 44 will shred the material, which will then pass through the gaps 7 into the 80 interior of the drum. The material passing into the drum passes down through a spider head 46 (see Fig. 1) and falls into a suitable hopper 47 near the floor, which if desired may be of conical form as shown and connected to a duct leading down through the 85 floor to carry the material away.

In order to effect the adjustment of the shredder bars 6, the shredder bars are mounted on the drum in such a way that they are 90 capable of rotation on their vertical axes. In the present instance I provide an individual independent adjusting device corresponding to each bar; for this purpose the ends of the bars are provided with threaded stems 48 (see Fig. 1) which pass through flanges 49 at the ends of the drum, at which point they are provided with clamping nuts 50 which clamp against the flanges for holding the bars in any adjusted position. In 95 order to adjust the bars with nicety, each bar is provided with two set screws 51 (see Fig. 6) which are disposed slightly eccentric to the longitudinal axis of the bar. These set screws abut against the circumferential 100 outer face 52 of the drum at this point. Each set screw is threaded into the bar and is provided with a check nut 53. It will be evident that these set screws will hold the bars rigidly in any adjusted position. By 105 tightening up one of the set screws and loosening the other, it will also be evident that the angle of the blades 42 may be very nicely adjusted.

In order to adapt the machine for operating on different kinds of material, I prefer to provide a variable drive mechanism 54 (see Fig. 1) for driving the vertical feed shafts 25 which correspond to the different feeding mechanisms in the guideways 8. 115 This variable driving mechanism may be driven from the vertical shaft 5 through bevel gears 55, and may include a horizontal shaft 56 carrying a splined roller 57 which runs on the upper face of a clutch 120 disc 58 carried on the upper end of a main vertical drive shaft 59. The lower end of this drive shaft 59 may serve as the individual drive shaft for one of the guideways, but in addition to this it performs the func- 125 130

tion of driving a series of cross shafts 60 which extend across the guideways (see Fig. 2). The cross shaft 60 which is adjacent to the vertical shaft 59 is driven through suitable bevel gears 61. Each individual feed shaft 25 is provided with a bevel gear 62 which is driven by a bevel gear 63 on one of the shafts 60 and this bevel gear 63 also operates to drive a bevel gear 64 on the cross shaft 60 next on the left. In this way these cross shafts 60 and their associated bevel gears operate as a driving train extending all around the drum to drive all of the feeding mechanisms.

The vertical shaft 5 may be driven by a belt pulley 65 (see Fig. 1) through a pinion 66 and gear wheel 67, and to prevent extensive injuries to the mechanism the shaft may be driven through shearing pins 68 which drive the shaft 5 through a keyed collar 69.

In the operation of such a machine it may happen that a foreign substance, for example a piece of wood or iron, will find its way into the material which is being fed to the shredding devices. If that should happen, under ordinary circumstances the shredding devices would be broken and possibly the shredder drum would be wrecked. In order to prevent such contingency, I prefer to provide a plate 70 on one of the vertical faces of the guideway 8 (see Fig. 2); that is to say, this plate is provided on the side toward which the shredding devices exert their pressure in the operation of the machine. The side wall 71 of the guideway at this point terminates considerably short of the drum so that the plate has a projecting portion extending beyond the wall 71 toward the drum. This plate 70 is strong enough to resist the normal pressure resulting from the normal operation of the machine, but if any hard object should become caught in the shredder blades, the overhanging portion of this plate 70 would immediately give way or fail and permit such an object to pass out of the guideway. The plate 70 may be secured in place by a bolt 72.

In the operation of the machine, by rotating a hand wheel 73 an inclined shaft 74 may be rotated, and this shaft, through the worm 75 and worm-wheel 76, may swing an arm 77 to and fro, the said arm being connected by a drag link 78 with a collar 79 carried by the splined wheel or roller 57. In this way, the roller 57 may be adjusted nearer to or further from the axis of the shaft 59 to alter the speed of driving of the shaft 59. In the position shown in Fig. 1, the shaft 59 will of course be driven at its slowest possible speed. The hub of the disc 58 is splined on the shaft 59 and is held up against the driving roller 57 with a constant pressure by a weighted lever 58^a, the forked end of which engages the slip collar 58^b on

the hub of the disc 58. The weight on this lever is indicated at 58^c.

I shall now describe the general mode of operation of the machine: The drum 4 is driven at a constant speed through the belt pulley 65 and intermediate gearing. The material to be shredded is placed in the guideways 8 in front of the follower plates 14. Through the variable feed mechanism, including the roller 57 and disc 58, the main vertical feed shaft 59 will be driven. Through this shaft 59 and through all the individual vertical feed shafts 25, the feed screws 10 of the guideways are rotated in a direction to advance the carriages of the feeding mechanism 9. This will hold the material to be shredded up against the face of the drum. As the drum rotates the material is shredded by the projecting edges of the blades 42 and passes through the gaps 7 into the interior of the drum. As each carriage arrives at the end of its travel, the pin 35 carried by it strikes the pin 36 and trips the clutch 26, 27. When this occurs, the weight 37 is carried over past the "dead-center" over the axis of the pivot pin 38 and swings down toward the right side (see Fig. 3) in such a way as to hold the clutch open. By removing the pin 17 the follower 14 may be swung back out of the way, and by operating the cam lever 18 the split nut 13 may be opened up so as to permit the carriage to be slid back to the outer end of the guideway. By means of the set screws 41 the angle of the shredder blades may be very nicely adjusted.

By rotating the hand wheel 73 the friction roller 57 may be adjusted on the face of the disc 58 so as to alter the driving speed of the shaft 59.

If any foreign body should come against the face of the drum, the plate 70 will give way so as to permit it to pass out of the guideway without injuring the shredding devices (see Fig. 2).

It is understood that the embodiment of the invention described herein is only one of the many embodiments this invention may take, and I do not wish to be limited in the practice of the invention, nor in the claims, to the particular embodiment set forth.

What I claim is:

1. In a shredding machine, the combination of a rotary drum, a plurality of guideways disposed substantially radially from the axis of the drum, a plurality of shredding bars extending longitudinally of the drum and carrying blades, feeding mechanism associated with the guideways for feeding the material to be shredded against the side of the drum, said shredding bars being disposed apart to permit the shredded material to pass into the interior of the drum,

a hopper below the drum for receiving the shredded material, and means above the drum for rotating the drum.

2. In a shredding machine, the combination of a frame, a rotary drum mounted to rotate on the frame on a substantially vertical axis, a drum shaft carrying the drum and extending upwardly therefrom, means for rotating the shaft, a plurality of feeding mechanisms for feeding the material to the drum, a substantially vertical feed-shaft with a disc at its upper end for driving the feed devices, and a shaft driven by the drum shaft and having a splined 15 driving roller engaging the face of the disc and movable across the disc to vary the driving ratio through the disc.

3. In a shredding machine, the combination of a frame, a rotary drum mounted 20 to rotate on the frame on a substantially vertical axis, a shaft carrying the drum and extending upwardly therefrom, means for rotating the shaft, a plurality of feeding mechanisms for feeding the material to the 25 drum, a substantially vertical feed-shaft for driving the feed devices, a variable drive-mechanism for driving the feed shaft, and automatic means for arresting the individual feeding mechanisms at a predetermined point.

4. In a shredding machine, the combination of a frame, a drum shaft mounted therein in a substantially vertical position, a shredder drum carried thereby, a plurality of guideways disposed substantially radially 35 from the axis of the drum, a follower corresponding to each guideway for feeding the material against the face of the drum, a substantially vertical feed shaft with

means for driving each follower from the same, and a variable driving mechanism for driving the feed-shaft.

5. In a shredding machine, the combination of a rotary drum having means for shredding material, a guideway for guiding material against the wall of the shredder drum to shred the same, said guideway having a relatively weak member adjacent the wall of the drum and against which the material being shredded is pressed by the force 45 exerted upon the material by the rotation of the drum in the shredding operation, said member operating to fail under an abnormal pressure and thereby prevent injury to the shredding devices carried by the drum. 55

6. In a machine of the kind described, a shredding drum having a plurality of shredding devices consisting of a bar of substantially triangular cross section, each bar being mounted on the drum with the long side 60 of the triangle disposed outwardly and the vertex disposed inwardly toward the axis of the drum, a cutter blade attached to an inclined face of each shredder bar, said bars being mounted so as to rotate on the longitudinal axis substantially coinciding with the plane of the long side of the triangle. 65

7. In a shredding machine, the combination of a rotary shredder, feeding mechanism for holding the material against the shredder, a driven disc, a driving roller for the disc, means for pressing the disc against the roller with a constant pressure, and means for driving the feeding mechanism from the disc. 75

Signed at Los Angeles, Calif., this 4th day of March, 1925.

ARTHUR R. ADAMSON.
